(**) Term: **14 Years**

(57) **CLAIM**

(21) Appl. No.: **29/212,077**

The ornamental design for a beverage holder in the shape of stacked tires, as shown and described.

(22) Filed: **Aug. 26, 2004**

DESCRIPTION

(51) **LOC (8) Cl.** **07-01**

FIG. 1 is a perspective view of a beverage holder in the shape of stacked tires without a beverage showing my new design.

(52) **U.S. Cl.** **D7/625**

FIG. 2 is a perspective view of the beverage holder in the shape of stacked tire of FIG. 1 holding a beverage can. The can that is shown in broken lines is for illustrative purposes only and forms no part of the claimed design.

(58) **Field of Classification Search** D7/603–608, D7/628, 619.1–625; D12/500, 501; 62/457.1–457.7; 215/392–396; 220/737, 739, 902, 903

FIG. 3 is a side view of the beverage holder of FIG. 1.

See application file for complete search history.

FIG. 4 is a top plan view of the beverage holder of FIG. 1; and,

FIG. 5 is a bottom plan view of the beverage holder of FIG. 1.
